UNITED STATES PATENT OFFICE

91,101

DESIGN FOR A CLOCK CASE

Matthew Covone, New Haven, Conn., assignor of one-half to Elizabeth H. Silver, New Haven, Conn.

Application September 30, 1933
Serial No. 49,390

Term of patent 7 years

To all whom it may concern:

Be it known that I, MATTHEW COVONE, a citizen of the United States, residing at New Haven, in the county of New Haven and State of Connecticut, have invented a new, original, and ornamental Design for a Clock Case, of which the following is a specification, reference being had to the accompanying drawing, forming part thereof.

Fig. 1 is a face view of a clock case showing my new design; and

Fig. 2 is a side view of the same.

I claim:

The ornamental design for a clock case as shown.

MATTHEW COVONE.
